DESIGN FOR A FOUNTAIN PEN
RECEPTACLE UNIT

Laszlo Moholy-Nagy, Chicago, Ill., assignor to
The Parker Pen Company, Janesville, Wis., a
corporation of Wisconsin

Application August 22, 1946, Serial No. 132,728

Term of patent 14 years

(Cl. D74—1)

To all whom it may concern:

Be it known that I, Laszlo Moholy-Nagy, a citizen of the United States, residing at Chicago, county of Cook, State of Illinois, have invented a new, original, and ornamental Design for a Fountain Pen Receptacle Unit, of which the following is a specification, reference being had to the accompanying drawings, forming a part thereof.

In the drawings:

Figure 1 is a top plan view of a fountain pen receptacle unit showing my new design;

Fig. 2 is a side elevational view thereof; and

Fig. 3 is a bottom plan view of the part shown in full lines in Figs. 1 and 2.

The essential features of my design reside in the parts shown in full lines.

I claim:

The ornamental design for a fountain pen receptacle unit, substantially as shown and described.

LASZLO MOHOLY-NAGY.
